CAR COUPLER

William J. Metzger, East Cleveland, Ohio, assignor to National Malleable and Steel Castings Company, Cleveland, Ohio, a corporation of Ohio

Application May 29, 1948, Serial No. 30,056

14 Claims. (Cl. 213—153)

1

This invention relates to car couplers for railway cars.

The main object of my invention is to provide means on a car coupler for increasing the horizontal gathering range of the couplers and for supporting a coupler in the event it is accidentally pulled out of the end of a car and thereby preventing it from dropping onto the track.

Another object is to provide means in the form of a shelf on a car coupler positioned below the knuckle thereof for cooperation with the shelf of a mating coupler to increase the horizontal gathering range of the couplers.

Another object is to provide preliminary aligning means for car couplers.

A further object is to provide a forwardly facing surface on a car coupler for cooperation with a similar surface on a mating coupler for aligning the couplers to enable coupling thereof even though the couplers are displaced relative to one another in a vertical direction a substantial amount.

A still further object is to provide a coupler having a forwardly facing coupler aligning surface positioned below the knuckle of the coupler and a coupler supporting portion adjacent the aligning surface.

Another object is to provide a novel shelf on a car coupler for underlying the knuckle and body of a mating coupler and adapted to support the latter coupler in the event it is accidentally disassociated from its draft rigging.

Other objects and advantages of my invention will be apparent from the following description of the invention taken in conjunction with the drawings in which:

Fig. 1 is a plan view of a coupler embodying my invention, coupled with a similar coupler (shown in dot-dash) and being shown in buffed position.

Fig. 2 is a front view of the coupler shown in Fig. 1.

Fig. 3 is an elevational view of the coupler shown in Fig. 1 supporting another coupler coupled therewith and corresponding to the condition wherein the latter has been pulled away from its associated draft rigging.

Fig. 4 illustrates the manner in which any invention serves to align two couplers from their angled position on one side of the centerline of the car, the knuckle of one coupler being open and the other closed.

Fig. 5 is a view similar to Fig. 4 but showing the couplers in angled position on the side of the centerline opposite from that shown in Fig. 4, the same knuckle being open.

2

Fig. 6 shows the couplers of Fig. 4 aligned to the position where the coupler knuckles have just come into contact.

Fig. 7 shows the couplers of Fig. 5 aligned to the position where the gathering wing of one coupler has just come into contact with the complementary socket of the mating coupler.

Fig. 8 is a plan view of a standard E coupler to which the invention has been applied.

Fig. 9 is a front view of the coupler shown in Fig. 8.

Fig. 10 illustrates the coupler shown in Fig. 8 forming the sole support for a similar coupler coupled therewith, and corresponding to the condition wherein the latter has been pulled away from its associated draft rigging.

Fig. 11 is an elevational view of a modified form of my invention.

Fig. 12 is a plan view of a further modification of my invention.

Referring particularly to Figs. 1 to 3 of the drawings there is shown a car coupler having a head 10, guard arm 12, and pivoted knuckle 14. The coupler, which is of the side operating type, is similar to that disclosed in my Patent No. 2,340,818, and has an opening 16 in the side of the coupler for a rotor lever (not shown) for operation of the coupler. The coupler is provided with gathering wings 18 and complementary sockets 19 the features of which are described and claimed in my copending application Serial No. 773,127, filed September 10, 1947.

The coupler will intercouple with all standard couplers now in service except those having interengaging guiding wings such as are provided on the A. A. R. Tightlock coupler.

The invention as applied to the present coupler comprises a shelf 20 which is positioned on the underside of the coupler and extends forwardly beyond front face 22 of knuckle 14 when the latter is in closed position. Shelf 20 comprises a horizontal supporting portion 24 and a sloping portion 26 extending forwardly and downwardly from portion 24. Portion 24 extends rearwardly from a point beneath the coupler knuckle to the front face of the coupler and extends laterally inwardly nearly to the centerline of the coupler. The shelf is spaced downwardly from the underside of the coupler to avoid any interference with the coupling of two couplers where one of them may be positioned considerably lower than the other. Also, sloping portion 26 affords a limited amount of vertical gathering action when one of the couplers is lower than the other by an

amount greater than that within which proper coupling can be effected.

Shelf 20 is formed with a depending wall 28 which is cylindrically curved at its forward portion, as at 30, and provides a buffing surface positioned a substantial distance forwardly of buffing face 22 of the knuckle when the latter is in closed position. It will be observed that surface 30 is of substantial vertical extent so that these surfaces upon engagement are effective to guide the mating couplers into position for coupling whether the couplers are located at the same height or displaced vertically relative to one another. Wall 28 is formed on one side of the shelf with a straight longitudinal portion as at 32 which extends rearwardly to the end of the shelf. On the other side of the shelf wall 28 is formed with a straight outwardly and rearwardly extending portion 34 which merges with a rearwardly extending portion 36. Wall 28 in addition to serving as a buffing and guiding surface as will be hereinafter described, acts as a reinforcement for the shelf. The shelf is joined to the coupler by means of cylindrical lug 38 and an upstanding flange 40 and may be cast integral with the coupler or welded thereto.

In Fig. 1 is seen the relationship of shelves 20 when the couplers are coupled and subjected to a force in buff. This view also clearly shows the manner in which the shelf of each coupler underlies the knuckle as well as the head of the opposing coupler.

In Fig. 3 is illustrated the manner in which the shelf serves to support a coupler which has been pulled out of its associated draft rigging and thereby prevent its dropping onto the roadbed or track. It will be noted that the coupler shown on the right, which for purposes of illustration is an A. A. R. Standard E coupler without a shelf applied thereto, is supported by shelf 20 at 42 and by the engagement between the knuckles of the two couplers at 44 and between the knuckle of the E coupler and the front face of the supporting coupler, at 46. The pulled out coupler is thus securely supported by the shelf in conjunction with the interengagement between the knuckles. It will be understood that where each of two coupled couplers is provided with a shelf then whichever of the couplers is pulled out will be supported by the other in the same manner as shown in Fig. 3.

Also, the shelf helps to prevent telescoping of cars during derailments or wrecks to the extent that the shelf, within the limits of its strength, will resist relative vertical displacement between the couplers as would cause a separation thereof.

In Figs. 4 to 7 is illustrated the manner in which the shelves cooperate to effect initial or preliminary gathering of couplers prior to coupling. In these views the couplers are similar in type to those shown in my application Serial No. 773,127. The couplers in Figs. 4 and 5 are shown in angled positions of such a degree that the wings 18 and sockets 19 are ineffective to gather the couplers. As may be seen in Figs. 4 and 5 the initial engagement of the couplers as they approach for coupling occurs between the shelves along the inner sides of curved surfaces 30 thereof. Thereafter as the couplers move together sliding occurs along surfaces 30 and the couplers are thereby guided to positions in which coupling can be effected. More specifically the contact between the shelves serves to gather the couplers, without prematurely closing the open knuckle, the amount necessary for the couplers to be coupled.

Considering particularly the positions of the couplers in Fig. 4 it is to be noted that the couplers are displaced beyond the gathering range of the coupler contours and therefore, if they were not provided with the shelves, coupling could not be effected because the open knuckle would close prematurely, causing the couplers to jack-knife. As the couplers move together from the position shown in Fig. 4 the shelves serve to guide the couplers so that engagement will eventually occur between the coupler knuckles as shown in Fig. 6, in which successful coupling is possible. From the latter position further gathering of the couplers to coupled position will take place in the usual manner as with couplers not provided with my shelf. Thus the shelves serve to guide the displaced couplers from a position in which normal coupling would be impossible to a position where the couplers are within the gathering range of the coupler contours so that normal coupling from the latter position is possible.

As the couplers move together from the position shown in Fig. 5 sliding occurs along the curved portions 30 of the shelves and the couplers are gathered thereby until they reach the position shown in Fig. 7, with one of wings 18 engaging the complementary socket 19 of the opposing coupler and the buffing face of the closed knuckle engaging the tail of the opposing knuckle. From this position the couplers are swung into alignment through the pivoting action occurring between the wing and socket as described in my aforementioned application, Serial No. 773,127.

Considering the angled positions of the couplers in Figs. 4 and 5, it is to be noted that the degree of displacement of the couplers from the longitudinal centerline of their respective cars is such that the couplers could not be coupled, without the preliminary gathering provided by the shelves. Thus the shelves serve to gather and align the couplers from a position in which normal coupling is impossible to a position in which they can be successfully coupled. This constitutes an important feature of the invention.

It is contemplated that buffing surface 30 of the shelf in addition to being curved in a horizontal plane may also be curved in a vertical plane as shown at 30a in Fig. 11. This will permit a greater area of contact between the couplers when one or both of the mating couplers is in a drooped position.

Referring to Figs. 8, 9 and 10, there is shown an A. A. R. Standard E coupler to which my improved shelf has been applied. The coupler comprises a guard arm 60, and a pivoted knuckle 62. The shelf 64 is similar to the shelf shown in Figs. 1, 2 and 3, except that the horizontally disposed rearward portion 66 of the shelf is elevated with respect to horizontal forward portion 68. It will be observed that elevated portion 66 is located so as to underlie the knuckle of a mating coupler. In the event the mating coupler is accidentally "pulled out" and angles about the knuckles and swings downwards, its body portion will engage sloping portion 70 of the shelf in addition to the binding of the knuckles at 72 and 74. This manner of supporting the coupler is shown in Fig. 10. However, in the event the "pulled out" coupler drops vertically downwardly its knuckle will rest on portion 66 of the shelf and simultaneously the coupler body will rest on sloping portion 70 of the shelf. Similarly in the event of a derailment, the coupler of the derailed car will drop vertically downwardly until its knuckle rests on elevated portion 66, in which case a smaller bending mo-

ment is applied to the shelf than when the supported coupler angles about the coupler knuckles and engages only the sloping portion 70. This will lessen the danger of shelf failure and thus afford increased protection to a derailed car by maintaining the couplers in coupled relationship.

While elevated portion 66 of the shelf has been shown in conjunction with the A. A. R. Standard E coupler, it is readily apparent that this feature may also be applied to the form of coupler shown in Figs. 1 and 2; thereby providing increased derailment protection to cars having couplers of the non-interlocking type coupled with this coupler.

It will be apparent that the shelf when applied to the E coupler will increase the gathering range of the coupler since it will function in the same manner as hereinbefore described. The initial contact between two approaching couplers will occur between the buffering surfaces of the shelves and the couplers will be guided into position from which they can be coupled in normal manner.

In Fig. 12 a modified form of contour for the buffering surface of the shelf is shown at 80. This surface includes a flat forwardly and outwardly extending surface 81 which is tangential to curved portion 75. This contour will further increase the gathering range of the coupler by causing the shelf of an opposing coupler to slide along the curved portion to the position from which coupling can be effected.

It will be understood that the application of my invention is not limited to the types of couplers shown, which were used for purposes of illustration only, and the shelf may be applied to all existing knuckle type couplers now in service to increase the gathering range thereof as well as to support a "pulled out" coupler.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A car coupler adapted for mating engagement with another similar coupler, said coupler having a head and a pivoted knuckle, said head having a forwardly extending shelf portion below said knuckle, said shelf being disposed within the lateral extremities of said knuckle and extending forwardly beyond said knuckle when the latter is in closed position, said shelf having a convexly curved buffering surface adapted for engagement with the buffering surface of the shelf of the other coupler to align the couplers during the coupling operation.

2. In a car coupler having a head and a pivoted knuckle, aligning means on said head for guiding two couplers into position for coupling comprising a shelf below said knuckle extending forwardly beyond said knuckle when the latter is in closed position, said shelf having a convexly curved buffering surface positioned on the knuckle side of the longitudinal centerline of the coupler.

3. In a car coupler having a head and a pivoted knuckle, aligning means on said head for guiding two couplers into position for coupling comprising a forwardly extending portion below said knuckle, said portion having a curved front surface adjacent the longitudinal centerline of the coupler and located forwardly of the buffering face

of said knuckle when the latter is in closed position.

4. In a car coupler having a head and a pivoted knuckle, aligning means on said head for engaging similar means on another coupler to guide the couplers into position for coupling, said means comprising a member disposed beneath said knuckle within the lateral extremities thereof having a front buffering surface positioned forwardly of the buffering face of said knuckle when the latter is in closed position, said surface being constructed and arranged to engage a corresponding surface of the other coupler prior to engagement between said knuckles of the couplers during the coupling operation.

5. In a car coupler having a head and a pivoted knuckle, aligning means on said head for engaging similar means on another coupler to guide the couplers into position for coupling, said means comprising a projection on the underside of said head extending forwardly of said knuckle when the latter is in closed position, said projection having a buffering surface positioned on the knuckle side of the coupler and adapted to engage a corresponding buffering surface on the other coupler prior to engagement between said knuckles of the couplers during the coupling operation.

6. In a car coupler having a head and a pivoted knuckle, aligning means on said head for engaging similar means on another coupler to guide the couplers into position for coupling, said means comprising a projection on the underside of the coupler positioned on the knuckle side of the longitudinal centerline of the coupler, said projection having a buffering surface positioned forwardly of the buffering face of said knuckle when the latter is in closed position.

7. In a car coupler having a head and a pivoted knuckle, a forwardly projecting shelf on said head for underlying portions of the knuckle and head of a similar coupler when two of such couplers are coupled together, said shelf being adapted to serve as a partial support for the other coupler in the event the latter is pulled away from its car, said shelf having a convexly curved buffering surface located adjacent the longitudinal centerline of the coupler and being adapted for engagement with a corresponding surface of the other coupler to align the couplers as they are moved together for coupling.

8. In a car coupler having a head and a pivoted knuckle, a shelf on said head adapted to underlie portions of the knuckle and head of another similar mating coupler coupled therewith, said shelf being adapted to serve as a partial support for one of said couplers in the event a coupler is pulled away from its car, said shelf being positioned on the knuckle side of the longitudinal centerline of the coupler and having a front buffering face adapted to engage the buffering face on the shelf of the mating coupler to align the couplers as they are moved together for coupling.

9. A car coupler adapted for mating engagement with another similar coupler, said coupler having a head and a pivoted knuckle, a forwardly extending shelf portion on said head below said knuckle, said shelf being disposed on the knuckle side of the longitudinal centerline of the coupler and extending forwardly beyond said knuckle when the latter is in closed position, said shelf having a convexly curved buffering surface adapted for engagement with the buffering surface of said shelf of the other coupler to align the couplers during the coupling operation, said shelf having a forwardly and downwardly sloping upper sur-

face for cooperating with the knuckle of the opposing coupler to raise the latter when it is in a dropped position as the couplers approach for coupling.

10. In a car coupler having a head and a pivoted knuckle, a shelf on said head adapted to underlie portions of the knuckle and head of another similar mating coupler coupled therewith, said shelf being adapted to serve as a partial support for one of said couplers in the event a coupler is pulled away from its car, said shelf being positioned on the knuckle side of the longitudinal centerline of the coupler and comprising a pair of vertically spaced horizontal supporting portions.

11. In a car coupler having a head and a pivoted knuckle, a shelf on said head below the knuckle and being adapted to engage the shelf of a laterally displaced mating coupler, as the couplers approach for coupling, to guide the couplers into position from which the couplers can be coupled, said shelf having a buffering surface comprising a forwardly and outwardly extending surface positioned on the knuckle side of the longitudinal centerline of the coupler and located forwardly of the coupler knuckle when the latter is in closed position.

12. A guiding and supporting shelf for a car coupler of the knuckle type, said shelf including a curved vertical guide surface facing forwardly of the coupler and laterally toward the longitudinal centerline thereof, said shelf being adapted for engagement with a similar shelf on an opposing coupler for aligning the couplers, said shelf having a substantially horizontal surface adapted

to support portions of the knuckle and head of the opposing coupler in the event the latter is accidentally displaced downwardly.

13. Aligning means for a coupler of the knuckle type comprising an extension projecting forwardly from the head of the coupler and located beneath the knuckle thereof, said means including a curved vertical guide surface facing forwardly of the coupler and laterally toward the longitudinal centerline thereof and adapted to engage the corresponding vertical face of similar means on an opposing coupler to align the couplers during the coupling thereof.

14. A supporting shelf for a car coupler of the knuckle type comprising a projection extending forwardly from the head of the coupler and disposed on the knuckle side of the longitudinal centerline of the coupler, said projection being adapted to underlie portions of the knuckle and head of an opposing coupler for supporting the latter in the event the same is accidentally displaced downwardly.
